COMBINED KNIFE RACK AND SHELF

Samuel L. Gerson, Wilmington, Del.

Application June 17, 1957, Serial No. 46,625

Term of patent 14 years

(Cl. D44—29)

FIG. 1.

FIG. 2.

FIG. 3.

FIG. 4.

FIG. 5.

The back of the combined knife rack and shelf is plain and unornamented.

I claim:

The ornamental design for a combined knife rack and shelf, substantially as shown and described.
